US00D879823S

(12) **United States Design Patent** (10) Patent No.: **US D879,823 S**
(45) Date of Patent: **** Mar. 31, 2020**

(54) **DISPLAY SCREEN WITH GRAPHICAL USER INTERFACE**

(71) Applicant: **Twitter, Inc.**, San Francisco, CA (US)

(72) Inventors: **Tyler Jan Hansen**, San Francisco, CA (US); **Kayvon B. Beykpour**, San Francisco, CA (US); **Joseph Harold Bernstein**, San Francisco, CA (US); **Aaron William Wasserman**, San Francisco, CA (US); **Nils Victor Rocine**, San Francisco, CA (US); **Alexander Kayvon Khoshnevisan**, San Francisco, CA (US); **Geraint John Davies**, Bodorgan (GB)

(73) Assignee: **Twitter, Inc.**, San Francisco, CA (US)

(**) Term: **15 Years**

(21) Appl. No.: **29/674,317**

(22) Filed: **Dec. 20, 2018**

Related U.S. Application Data

(62) Division of application No. 29/589,739, filed on Jan. 4, 2017, now Pat. No. Des. 856,350, which is a division of application No. 29/522,245, filed on Mar. 27, 2015, now Pat. No. Des. 780,785.

(57) **CLAIM**

What is claimed is the ornamental design for a display screen with graphical user interface, as shown and described herein.

DESCRIPTION

The FIGURE is a front view of a display screen with graphical user interface.

The broken line showing of the device illustrates environmental structure and forms no part of the claimed design. The broken line showing of the display screen and portions of the graphical user interface illustrate portions of the article and form no part of the claimed design.

1 Claim, 1 Drawing Sheet
